SINK

James A. Tiller, Louisville, Ky., assignor to American Radiator & Standard Sanitary Corporation, New York, N.Y., a corporation of Delaware

Filed Aug. 26, 1960, Ser. No. 61,898

Term of patent 14 years

(Cl. D4—2)

FIGURE 1 is a top perspective view of a sink showing my new design; the opposite side thereof being substantially the same as that shown.

FIG. 2 is a top plan view thereof; and
FIG. 3 is a front elevation.

My design for a sink is characterized by the brim portion thereof, the lower edge of the brim being substantially parallel with the bottom edge of the sink bowl and the top edge of the brim sloping from front to rear, as shown.

I claim:

The ornamental design for a sink, substantially as shown and described.
